UNITED STATES PATENT OFFICE.

LEOPOLD A. WISE, OF NEW YORK, N. Y.

LOCK.

No. 921,048.

Specification of Letters Patent. Patented May 11, 1909.

Application filed October 20, 1908. Serial No. 458,601.

To all whom it may concern:

Be it known that I, LEOPOLD A. WISE, a citizen of the United States, residing at New York city, in the county of New York and State of New York, have invented certain new and useful Improvements in Locks, of which the following is a specification, reference being had to the accompanying drawings.

10 My invention relates to improvements in locks, and particularly to improvements in combination locks adapted for use upon doors; and an object of my invention is to provide a lock of the character just described which will be simple in construction, comparatively cheap in manufacture and most efficient, secure and durable in use.

In the drawings illustrating the principle of my invention, and the best mode now known to me of applying that principle, Figure 1 is an edge view of a portion of a door provided with my new lock; Fig. 2 is a view of the outside of the same; Fig. 3 shows the inside of the door illustrated in Figs. 1 and 2; Figs. 4, 5 and 6 show the inside lock mechanism corresponding to three different positions of the latch-locking spindle; Figs. 7, 8 and 9 are outside end views corresponding to Figs. 4, 5 and 6; Fig. 10 is a section on the line 30 A—A of Fig. 1; Fig. 11 is a front view of the tumblers detached; Fig. 12 is a section on the line B—B of Fig. 11; Fig. 13 is a perspective showing the bolt mechanism and its attached parts; Fig. 14 is a plan of the bolt mechanism, the tumbler-dog being in engagement with the tumblers; Fig. 15 is a section on line C—C of Fig. 14 and shows different positions of the tumbler-dog; Fig. 16 is a detail showing the locking device for the bolt; Fig. 17 is a detail 40 of the actuating spindle; and Fig. 18 is an end view of the same looking in the direction of the arrow D in Fig. 17.

The lock is provided with a housing *a* and a cover plate *b*. Near the center of the back 45 of the housing *a* there is formed an annular flange or hub *c* which projects inwardly. The back of the housing *a* is further formed with an inwardly-extending stud *d* and two inwardly-projecting guide plates *e*, between 50 which is slidably fitted the bolt or latch *f*. The outer end of the latter is beveled and

projects through an opening *g* in one side of the housing *a*. The inner end of the bolt or latch *f* is formed with a socket *h* (Fig. 13), in which is fitted one end of a coil spring *i*, the other end of which is fastened to the stud *d*. The coil spring *i* tends to force the bolt or latch *f* outwardly. Into the central hole of the hub or annular flange *c* is screwed one end of a sleeve *j*, the other end of which screws into a socketed bearing or sleeve *k*. The sleeve *j* is formed with an annular flange *m* on its exterior and the socketed bearing *k* is formed with a similar annular flange *n* on its outer wall. Upon the outer end of the socketed bearing or sleeve *k* is screwed a ring *o*, between which and the flange *n* is rotatably mounted the initial tumbler *p*. Between the annular flange or hub *c* and the annular flange *m* is rotatably mounted the 70 final tumbler *q* (Fig. 12), and between the flanges *m* and *n* is rotatably mounted the intermediate tumbler *r*. The initial tumbler *p* is formed with a series of holes *s*, arranged on a circle having for its center the center of the 75 tumbler (Fig. 11).

Through a hole in the outer end of the socketed bearing *k* there projects, into the sleeve *j*, the inner end of the actuating spindle *t*, which carries the driving disk *u* formed 80 with a pair of driving pins *v*, which are adapted to engage a pair of the holes *s*. The actuating spindle *t* is formed with a longitudinal series of holes *w* each of which is adapted to receive the inner end of a pin *x* by which the 85 disk *u* is fastened to the spindle *t*. The position of the driving disk *u* may be varied to adapt the lock for use with doors *y* of different thicknesses, as is shown by the dotted lines in Fig. 12.

On its face opposite to the intermediate tumbler *r*, the initial tumbler *p* is formed, with a stud *z* adapted to engage the stud 2 which projects from the intermediate tumbler *r* toward the initial tumbler *p* and the 95 final tumbler *q* is formed on its face opposite to the intermediate tumbler *r* with a stud 3 which is adapted to be engaged by the stud 4 which projects from the intermediate tumbler *r* toward the final tumbler *q*. The initial tumbler *p* is formed with a peripheral 100 notch or recess 5, one wall of which is curved

2
at its junction with the circumferential wall of the tumbler, as is shown at 6 in Fig. 11. The intermediate tumbler *r* is formed with a peripheral notch 7, as is shown in Fig. 11; 5 and the final tumbler *q* is formed with a peripheral notch 8, similar to the peripheral notch 7 of the intermediate tumbler *r*. The latch *f* is formed with an inwardly extending arm 9 from which projects a pair of fingers 10. When the latch *f* is in its locking position, one of the fingers 10 lies over the driving disk *u* and prevents the spindle *t* from being withdrawn; but when the latch *f* is pushed inwardly until the line 11 registers 10 with the wall of the opening *g* in the housing *a*, the fingers 10 assume the position shown by the dotted lines in Fig. 4 and thereby permit the withdrawal of the actuating spindle *t* for the purpose of changing the combination. 15

Pivotedly mounted upon the inner face of the latch *f* is a tumbler dog 12, the head of which is formed with a cam face 13 (Fig. 13). The cam portion 13 of the tumbler dog is 20 adapted to enter the notch or recess 5 in the initial tumbler *p*, while the other portion of the head of the tumbler dog is adapted to lie in the notches 7 and 8 in the intermediate and final tumblers *r*, *q*. It will be obvious 25 that in turning the initial tumbler, the latter may be turned so far that the cam portion 6 of the wall of the recess 5 will act upon the cam face 13 of the head of the tumbler dog 12, so as to force the latter out of the notches 30 5, 7, 8 (Fig. 15).

Above the opening *g*, the housing *a* is formed with a recess 14, the bottom wall of which is formed with a central hole through which extends the threaded shank 15 of a 35 screw, the disk-like head 16 of which lies in the recess 14 and is formed with a diametral lug 17 (Fig. 16). The threaded shank 15 screws into the socket 18 in one end of the locking spindle 19, the other end 20 of which 40 is journaled in the housing *a*. The latch *f* is formed with a channel 21 and the latch-locking spindle 19 is formed with a locking-pin 22; and when the latch *f* is forced inwardly until the channel 21 lies in the path 45 of rotation of the locking-pin 22, the latch may be locked in that position by merely turning the locking spindle 19 by means of the lug 17. It will be observed that the latter lies in the recess 14 and is thereby shielded 50 from being tampered with readily. Fig. 55 6 shows the latch *f* locked in its innermost position and in this position it will be observed that one of the fingers 10 lies over the driving disk *u* and thereby prevents the removal of the actuating spindle *t*. Again, in 60 this position of the latch *f* the door may be readily opened and closed without operating the lock; that is, the lock is made inactive.

Upon the locking spindle 19 near its center 65 is mounted a locking lug 23, which may, by

turning the locking spindle 19, be interposed in the path of travel of the head of the tumbler dog 12. When the locking lug 23 is thrown into the position shown in Fig. 5; that is, downwardly, and the tumbler dog is 70 raised out of the notches, 5, 7, 8 in the tumblers and into the position shown in Fig. 5, the latch is locked in its outermost position and cannot be forced inwardly except by bringing the notches 5, 7, 8 into register 75 so that the head of the tumbler dog 12 will fall into these notches, in which case by rotating the tumblers the latch *f* may be drawn inwardly. In other words, the latch *f* is locked against movement by persons 80 other than those having the combination to the lock. The locking-pin 22 and the locking-lug 23 both serve to limit by their engagement with the back of the housing *a*, the rotation of the locking spindle 19. 85 Lines 32, 33 and 34, serve to indicate to the operator the points to which to bring the lug 17, in order that the locking spindle may have the several positions shown in Figs. 4, 5, and 6, respectively.

The door *y* is formed with a cylindrical opening 25 through which extends the actuating spindle *t* and over the outer end of which is placed the dial plate 26. The actuating spindle *t* passes through a central hole 95 in the dial plate 26 and is provided at its outer end with a knob 27 formed with an index mark 28. The knob 27 covers the screws 31 by which the plate 26 is fastened on the door (Fig. 10).

Fig. 4 shows the normal position of the parts of the lock. When it is desired to change the combination the latch *f* is forced inwardly until the line 11 registers with the wall of the opening *g* in the housing *a*. In 105 this position of the latch, the fingers 10 are moved from over the driving disk *u* so that the latter may be withdrawn between the fingers 10, thereby disengaging the driving-pins *v* from the holes *s* in the initial tumbler 110 *p* (Fig. 12). The actuating spindle may now be rotated without rotating the tumblers; and the driving pins *v* may be forced back into a new pair of holes *s*, thereby bringing the index mark 28 opposite a new 115 number on the dial-plate.

If one who does not know the combination attempts to ascertain what it is and succeeds in bringing the tumbler-notches 5, 7, 8 into register, so that the head of the tumbler-dog 12 falls by its own weight into these notches in the way that it is adapted and designed to do, he nevertheless may fail to open the lock; for, if he turns the tumblers until the curved portion 6 of the initial tumbler *p* bears 125 against the cam face 13 of the head of the tumbler-dog 12, the latter will be raised from out of the notches and the combination will be lost to the party seeking it.

The back of the housing *a* is formed with a 130

slot 29, through which extends the shank of a thumb-piece 30. The latter engages the latch *f* and allows the lock to be opened from the inside of the room.

5 I claim:

1. In a lock the combination with a housing and a dial-plate, of a bolt; a series of tumblers within said housing; means for connecting said bolt and tumblers; means detachably secured to one of said tumblers for actuating the same; and means carried by said bolt for preventing the detachment of said tumbler-actuating means from said tumblers.

15 2. In a lock, the combination with a housing and a dial-plate, of a bolt; a series of tumblers within said housing; means for connecting said bolt and tumblers; means detachably secured to one of said tumblers for actuating the same; and means carried by said bolt for preventing the detachment of said tumbler-actuating means from said tumblers, when in one position; said bolt-carried means being adapted and designed to 20 be positioned by the movement of said bolt to allow the detachment of said tumbler-actuating means from said tumblers.

3. In a lock, the combination with a housing and a dial-plate, of a bolt; a series of 30 tumblers within said housing; means for connecting said bolt and tumblers; means detachably secured to one of said tumblers for actuating the same; and a pair of fingers carried by said bolt; said fingers being separated by an interval sufficient to permit the movement therethrough of said tumbler-actuating means and one of said fingers normally preventing the detachment of said tumbler-actuating means from said tumblers.

40 4. In a lock, the combination with a housing, of a pair of sleeves, the outer end of one of which is mounted in said housing and the inner opposed ends of which fit into each other, whereby said sleeves form a bearing; said sleeves being formed with circumferential grooves; tumblers mounted in said grooves; and means for actuating said tumblers.

45 5. In a lock, the combination with a housing, tumblers mounted therein and means for actuating said tumblers; of a bolt; a tumbler-dog carried by said bolt and adapted to connect the latter with said tumblers; and movable means for preventing the movement of said bolt, when the latter is thrown outwardly in locking position and when said tumbler-dog is out of engagement with said tumblers; the last-named means being operable from without said housing from the side thereof out of which projects said bolt.

60 6. In a lock, the combination with a housing, tumblers mounted therein and means for actuating said tumblers; of a bolt; a tumbler-dog carried by said bolt and adapted

to connect the latter with said tumblers; and a locking device which in one position holds said bolt in said housing and thereby renders the lock inactive and in another position prevents the movement of said bolt, when the latter is thrown outwardly in locking position; said device being operable from without said housing from the side thereof out of which projects said bolt.

70 7. In a lock, the combination with a housing, tumblers formed with notches and mounted therein and means for actuating said tumblers; of a bolt; a tumbler-dog carried by said bolt and adapted to engage the notches of said tumblers; and a movable locking device for preventing the movement of said bolt, when said tumbler-dog is out of engagement with the notches of said tumblers; said device being movable from without the housing and permitting said tumbler-dog to engage the notches of said tumblers, while said device is in operative position.

75 8. In a lock, the combination with a housing; tumblers formed with notches and mounted therein and means for actuating said tumblers; of a bolt; a tumbler-dog carried by said bolt and adapted to engage the notches of said tumblers; and a movable locking device formed with a lug and adapted and designed to be operated from without 80 the housing to throw said lug into and out of the path of said tumbler-dog, when the latter is disengaged from the notches of said tumblers; said device permitting said tumbler-dog to engage the notches of said tumblers, 85 while said lug is in operative position.

90 9. In a lock, the combination with a housing, tumblers mounted therein and means for actuating said tumblers; of a spring-controlled bolt; a tumbler-dog carried by 95 said bolt and adapted to connect the latter with said tumblers; and a locking spindle which in one position holds said bolt in said housing and thereby renders the lock inactive and in another position prevents the movement of said bolt, when the latter is disconnected from said tumblers.

105 10. In a lock, the combination with a housing and tumblers mounted therein; of means for actuating the latter; and a spindle upon 110 which said means are mounted free to be moved therealong for different thicknesses of doors.

110 11. In a lock, the combination with a housing and tumblers mounted therein; of a 120 driving disk provided with means for engaging one of said tumblers; an actuating spindle provided with a series of holes distributed along its length; and a pin which engages said disk and is adapted to fit in said holes 125 for fastening said disk to said spindle at various points therealong.

12. In a lock, the combination with a housing and a tumbler mounted therein and formed with a series of holes; of a driving 130

disk provided with means for engaging detachably in said holes to connect said tumblers and disk together; and means for actuating said driving disk; the latter being
5 adjustable along the last-named means.

In testimony whereof I have hereunto set
my hand at said New York city this seven-

teenth day of October, A. D., 1908, in the presence of the two undersigned witnesses.

LEOPOLD A. WISE.

Witnesses:

JAMES HAMILTON,
ALBERT HAMILTON.
